REFRIGERATING APPARATUS

Donald F. Alexander, Oakwood, Ohio, assignor to
General Motors Corporation, Dayton, Ohio, a
corporation of Delaware

Application August 27, 1942, Serial No. 456,427

9 Claims. (Cl. 200—122)

This invention relates to refrigerating apparatus and more particularly to protectors for electric circuits.

Automatic thermal overload protectors have thermal elements heated by the current flowing through the electric circuit to open the electric circuit when the thermal element becomes heated above certain temperatures. The reclosing of the circuit takes place when the thermal element cools to a predetermined temperature. The cooling of the thermal element depends upon the environment or ambient temperature. Under continuous overload conditions the overload protector will trip and reset continuously permitting successive rushes of current through the electric circuit. When the ambient temperature is low the protector will reset at a more rapid rate so that the successive rushes of current are more frequent than when the ambient temperature is high. Where there are large electrical elements in the electric circuit, such as an electric motor the increasing frequency of the rushes of current through the motor increases the temperature of the motor windings and may damage the insulation.

It is an object of my invention to provide a protector having means for making the frequency of resetting substantially the same regardless of variations in the ambient temperature.

It is another object of my invention to compensate for the varying rate of cooling the operating element of the overload protector by an automatic reset adjustment.

It is another object of my invention to provide a protector having a reset adjustment responsive to ambient temperature.

It is still another object of my invention to provide a protector having a bimetal operated reset adjustment.

I have found that protectors of certain types, such as the bimetallic disk type, have inherently large differentials. Such protectors, particularly when they are mounted upon an electric motor, reset too slowly for certain applications, such as the preservation of frozen foodstuffs.

It is therefore another object of my invention to provide a means for reducing the on-off temperature differential of thermal motor protectors and thereby reducing the resetting time.

It is another object of my invention to provide a bimetal operated device for reducing the differential of a thermal motor protector.

These objects are attained by providing a thermal motor protector with a bimetal operated reset adjustment for the toggle mechanism of the protector in which the bimetal is located in and responsive to the ambient air, so that the differential of the protector is increased under cold ambient temperature conditions in order that the frequency of resetting under continued overload

conditions is substantially the same, as under warm ambient temperature condition. In the modified form, a bimetal heated by an electric heater which is energized upon the opening of the protector changes the open circuit position of the bimetal so as to raise the resetting temperature of the protector in order to reduce the resetting time.

Further objects and advantages of the present invention will be apparent from the following description, reference being had to the accompanying drawing wherein a preferred form of the present invention is clearly shown.

In the drawing:

Fig. 1 is a view, partly diagrammatic, showing a motor protector embodying one form of my invention operating under cold ambient temperature conditions;

Fig. 2 is a view similar to Fig. 1 with the protector tripped to open circuit position operating under high ambient temperature conditions;

Fig. 3 is a graph in which the time temperature cycles of the protector are plotted for high and low ambient temperatures both with and without compensation for cold ambient temperatures;

Fig. 4 is another form of motor protector embodying my invention;

Fig. 5 is one form of wiring diagram for the protector shown in Fig. 4;

Fig. 6 is another form of wiring diagram for the protector shown in Fig. 4; and

Fig. 7 is a graph illustrating the cycles of the motor protector of Fig. 4 without and with my invention.

Referring now to the drawing and more particularly to Figs. 1 and 2, there is shown a thermal overload protector 20 including a casing 22 of electrical insulating material provided with an operating bimetal 24 provided with an adjustment 26. The bimetal 24 is connected to one end of a tension toggle spring 28 having its other end connected to the free end of a toggle lever 30. The free end of the toggle lever 30 is operatively connected to a contact carrying strip 32 carrying the movable switch contact 34 which cooperates with a stationary switch contact 36.

The stationary contact 36 is connected to one of the supply conductors 38 of an electric circuit, while the contact carrying strip 32 is connected to an electric heater 40 which is provided for heating the cantilever bimetal strip 24. The electric heater 40 is connected to the remainder of the electric circuit which may include an electric motor 42 which in turn is connected to the other supply conductor 44. The bimetal 24 is so adjusted by the adjusting screw 26 and the heater 40 is made of such a size that when an electric current sufficient to endanger the electric motor 42 passes through the circuit, the bimetal 24 will be heated sufficiently to cause it to

curl upwardly as shown in Fig. 2 to trip the toggle spring 28 and the toggle lever 30 to the open circuit position as shown in Fig. 2.

The resetting of the protector depends upon the rate of cooling of the bimetal 24. The graph in Fig. 3 shows, in the light solid line, a temperature time curve designated by the reference character 48 in which the bimetal 24 is illustrated as heating up to a predetermined high temperature at which the protector trips to the open position as shown in Fig. 2. The protector then cools to a temperature, for example, of 135° F. at which temperature the bimetal has cooled sufficiently to reset the protector contacts. The graph illustrates the successive tripping and resetting of the protector in regular cycles during the continuing of the overload.

The light dotted line designated by the reference character 48 illustrates a slightly slower rise in temperature of the bimetal 24 under overload conditions in a cold room followed by more rapid cooling to the same resetting temperature followed by tripping and subsequent resetting in regular cycles. It will be seen from this graph that where the resetting temperature is the same, that about three cycles of the protector takes place under high ambient temperature conditions, while about four cycles takes place under cold room conditions. Also, for each cycle the length of time the current is allowed to rush through the circuit is just as long or in fact a trifle longer under the cold ambient temperature conditions than under the high ambient temperature conditions. The greater length of time the motor 42 is connected to the supply source the more its windings will be heated. If the protector is adjusted to allow the highest possible loading of the motor during warm room conditions, under which it is ordinarily desired that the motor operate to its fullest capacity, then the motor will be adequately protected under low ambient temperature conditions and the insulation of the windings may be damaged if an overload should occur under the low ambient temperature conditions.

I overcome this difficulty by lowering the resetting temperature under low ambient temperature conditions so that the frequency of the resetting cycles is just as long or possibly a trifle longer during low ambient temperature conditions. For example, I may reduce the resetting temperature under low ambient temperature conditions to about 120° F. This will extend the cooling cycle of the protector under low ambient temperature conditions as illustrated by the double dot and dash lines designated by the reference character 50 in Fig. 3. This change in the reset temperature extends the first cooling cycle of the graph 48 to a lower temperature thereby increasing its length so that when the protector closes, the next heating cycle of the protector will bring the tripping point of the protector substantially at the same time as the protector would trip under high ambient temperatures. In this way the frequency of tripping and resetting is made substantially the same for high and low ambient temperature conditions.

To carry this out, I have provided a movable reset regulating pin 52 which determines the circuit closing tripping position of the toggle lever 30. When this movable resetting pin 52 is in its uppermost position the differential of the toggle is increased so that the bimetal 24 must be cooled through a temperature of 120° F., before the toggle will permit tripping of the protector to the closed circuit position. When the pin 52 is

in its lowermost position the differential of the toggle is reduced so that the resetting temperature is raised to 135° F. It should be noted that the opening of the protector is not affected in any way by the adjustment of the pin 52, since the angularity of the toggle lever 30 is determined by the location of the stationary contact 36 upon the opening of the protector and the angularity of the toggle lever 30 in its extreme position determines the tripping temperature.

To move the pin 52 downwardly under high ambient temperature conditions to lower the reset temperature under low ambient temperature conditions, I provide a cantilever bimetal 54 outside the casing 52 where it is responsive to ambient temperature. The high expansive material of the bimetal is located on the upper side so that as the ambient temperature rises it will curl downwardly and move the pin 52 downwardly to raise the resetting temperature of the protector, for example, to 155° F. When the ambient temperature is low the bimetal 54 will curl upwardly, as shown in Fig. 1, to allow pin 52 to move upwardly to lower the resetting temperature of the protector, for example to 120° F. The bimetal 54 may assume intermediate position or temperatures for intermediate ambient temperatures. The bimetal 54 may be adjusted by the adjusting screw 56 to vary the resetting temperatures. By this device I provide adequate adjustment for ambient temperature, so that the frequency of the resetting cycles of the protector is substantially the same under varying ambient temperature conditions. At the same time, the tripping temperatures are kept substantially the same since they are substantially entirely governed by the heating effect of the electric heater 40.

In Fig. 4 I have shown another form of my invention in which the thermal operating element 121 is in the form of a dished bimetal disk enclosed within a casing 123 of electrical insulating material which is provided with a groove 125 for retaining the edges of the disk 121. The disk 121 carries a movable contact which is adapted to make contact with a stationary contact 127. The stationary contact 127 is connected to a supply conductor 130 while the disk is connected to a conductor 132. The disk 121 is heated by an electric heater 134, so chosen as to heat the bimetal disk 121 sufficiently when the safe operating current of the electric circuit is exceeded to cause it to snap to the dot and dash line position, shown in Fig. 4.

These bimetal disks have an inherently large temperature differential between their snapping from one position to another. It has been found where such disks are used for certain applications, that the resetting time is too long. One example of this is the refrigeration of frozen foodstuffs wherein if the system is deenergized for a considerable period of time, the frozen foods will rise above freezing temperature thereby reducing their quality and subjecting them to possible spoilage. To hasten the resetting of the bimetal disk 121 to closed circuit position, I provide a second bimetal 136 against which the bimetal disk stops when in the open circuit position. This bimetal 136 is heated by an electric heater 138 which is placed in shunt with the protector switch 127, so that when the protector contacts are opened the heater 138 will be energized to heat the bimetal 136 to cause the bimetal 136 to curl toward the bimetal disk 121 for the purpose of pushing mechanically the bimetal disk 121 toward its closed circuit posi-

tion. This will raise the temperature to which the bimetal disk 121 snaps to closed circuit position.

The heater 134 may be arranged in the circuit as shown in Fig. 5 in which it is in series with the switch contact 127 and the heater 138, or as shown in Fig. 6 in which the heater 134 is in series only with the switch contact 127 and in parallel with the heater 138. Whenever it is desired not to increase the speed of resetting, the switch 140 may be opened to prevent the energization of the heater 138. Fig. 7 shows one cycle designated by the reference character 141 in which the switch 140 is opened to deenergize the heater 138 to allow the protector to operate upon a wide differential. It also shows several cycles designated by the reference character 143 in which the switch 140 is closed to allow the heater 138 to operate and assist the resetting of the disk 121, so that the resetting occurs at the higher temperature and in a shorter time. As shown the resetting is accomplished in less than half the time the heater 136 is used. Thus this device increases the usefulness of this type of protector, and also other types of thermal protectors which do not reset rapidly enough. Obviously the heater 138 could be used upon the protector shown in Fig. 1 to heat the bimetal 54.

While the form of embodiment of the invention as herein disclosed, constitutes a preferred form, it is to be understood that other forms might be adopted, all coming within the scope of the claims which follow.

What is claimed is as follows:

1. A protector for an electric circuit including an operating element, means for operating said operating element in response to current-flow through the electric circuit, means controlled by said operating element for opening said electric circuit, reset regulating means for regulating only the reclosing of said electric circuit, and means for varying said regulating means in response to ambient temperatures.

2. A protector for an electric circuit including a thermal operating element, means for heating said element in response to the flow of electric energy through said circuit, means controlled by said operating element for opening said electric circuit when said operating element reaches a predetermined temperature, reset regulating means for regulating the temperatures at which the operating means recloses the electric circuit, and bimetal means for varying said reset regulating means.

3. A protector for an electric circuit including a thermal operating element, means for heating said element in response to the flow of electric energy through said circuit, means controlled by said operating element for opening said electric circuit when said operating element reaches a predetermined temperature, temperature responsive means for changing the temperature at which the circuit is reclosed independently of the circuit-opening temperature, and heating means energized in response to the opening of said protector for heating said temperature responsive means.

4. A protector for an electric circuit including an operating element, means for operating said operating element in response to current-flow through the electric circuit, means controlled by said operating element for opening said electric circuit, reset regulating means for regulating only

the reclosing of said electric circuit, a casing enclosing said element and all said above mentioned means, and temperature responsive means located outside said casing and having an operating connection with said reset regulating means for varying said reset regulating means.

5. A protector for an electric circuit including an operating element, means for operating said operating element in response to current-flow through the electric circuit, means controlled by said operating element for opening said electric circuit, reset regulating means for regulating only the reclosing of said electric circuit, a casing enclosing said element and all said above mentioned means, and a bimetal strip located outside of and subject to the environment temperature of said casing and having an operating connection with said reset regulating means for varying said reset regulating means according to environment temperatures.

6. A protector for an electric circuit including an operating element, means for operating said operating element in response to current-flow through the electric circuit, means controlled by said operating element for opening said electric circuit, reset regulating means for regulating only the reclosing of said electric circuit, a casing enclosing said element and all said above mentioned means, and temperature responsive means located outside said casing and having an operating connection with said reset regulating means for varying said reset regulating means, and means for adjusting said temperature responsive means to vary the relationship between environment temperature and the reclosing of the electric circuit.

7. A protector for an electric circuit including a bimetal operating element, an electric heating means located in heat transfer relationship with said operating element and connected in series with said electric circuit for operating said operating element, means controlled by said operating element for opening said electric circuit, and reset regulating means for regulating only the reclosing of the electric circuit comprising a cantilever mounted bimetal strip.

8. A protector for an electric circuit including a bimetal operating element, an electric heating means located in heat transfer relationship with said operating element and connected in series with said electric circuit for operating said operating element, means controlled by said operating element for opening said electric circuit, and reset regulating means for regulating only the reclosing of the electric circuit comprising a cantilever mounted bimetal strip and arranged to reduce the operating differential of the protector upon a rise in ambient temperature.

9. A protector for an electric circuit including a thermal operating element, means for heating said element in response to the flow of electric energy through said circuit, means controlled by said operating element for opening said electric circuit when said operating element reaches a predetermined temperature and for closing said circuit when said operating element cools, temperature responsive means for varying the operation of said operating element and means controlled thereby, and heating means energized in response to the opening of said protector for heating said temperature responsive means.

DONALD F. ALEXANDER.
